US00D529949S

(12) **United States Design Patent** (10) Patent No.: **US D529,949 S**
Murakami et al. (45) Date of Patent: **** Oct. 10, 2006**

(54) **DEVELOPER SUPPLYING CONTAINER**

(75) Inventors: **Katsuya Murakami**, Toride (JP);
Kyoichi Ando, Fuku (JP); **Yasuhiro**
Morishita, Nerimia-ku (JP)

(73) Assignee: **Canon Kabushiki Kaisha**, Tokyo (JP)

(**) Term: **14 Years**

(21) Appl. No.: **29/244,363**

(22) Filed: **Dec. 9, 2005**

(30) **Foreign Application Priority Data**

Sep. 14, 2005 (JP) 2005-026550

(51) **LOC (8) Cl.** **16-03**

(52) **U.S. Cl.** **D18/43**

(58) **Field of Classification Search** D18/12,
D18/36, 40, 43, 44, 56; D14/462, 469-471,

(57) **CLAIM**

The ornamental design for a developer supplying container, as shown.

DESCRIPTION

FIG. 1 is a front view of a developer supplying container showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof; and,

FIG. 7 is a perspective view thereof.

1 Claim, 4 Drawing Sheets

FIG. 1

FIG. 2

FIG. 5

FIG. 6

FIG. 7

UNITED STATES PATENT AND TRADEMARK OFFICE
CERTIFICATE OF CORRECTION

PATENT NO. : Des. 529,949 S
APPLICATION NO. : 29/244363
DATED : October 10, 2006
INVENTOR(S) : Katsuya Murakami et al.

Page 1 of 1

It is certified that error appears in the above-identified patent and that said Letters Patent is hereby corrected as shown below:

On Title Page, Item (75) INVENTORS

“Kyoichi Ando, Fucu (JP); Yasuhiro Morishia, Nerimia-ku (JP)” should read
--Kyoichi Ando, Fuchu (JP); Yasuhiro Morishia, Nerima-ku (JP)--.

Signed and Sealed this

Thirteenth Day of February, 2007

A handwritten signature in black ink, appearing to read "Jon W. Dudas". The signature is written in a cursive style with a large, stylized "J" and "W".

JON W. DUDAS
Director of the United States Patent and Trademark Office
